The ornamental design for a chess piece and head, as shown and described.

DESCRIPTION

FIG. 1 is a perspective view of a chess piece head, showing our new design;

FIG. 2 is a reduced front elevational view thereof, the broken line showing of the base is for illustrative purposes only, and forms no part of the claimed design;

FIG. 3 is a reduced right side elevational view thereof;

FIG. 4 is a reduced top plan view thereof;

FIG. 5 is a reduced left side elevational view thereof;

FIG. 6 is a reduced rear elevational view thereof; and,

FIG. 7 is a reduced bottom plan view thereof.
